UNITED STATES PATENT OFFICE.

ALLEN A. RUSSELL, OF MASSILLON, OHIO.

PNEUMATIC STRAW-STACKER.

SPECIFICATION forming part of Letters Patent No. 556,776, dated March 24, 1896.

Application filed June 8, 1895. Serial No. 552,181. (No model.)

To all whom it may concern:

Be it known that I, ALLEN A. RUSSELL, a citizen of the United States, and a resident of Massillon, county of Stark, State of Ohio, have 5 invented a new and useful Improvement in Pneumatic Straw-Stackers, of which the following is a full, clear, and exact description, reference being had to the accompanying drawings, making part of this specification.

10 My invention relates to an improvement in pneumatic straw-stackers.

The object of my invention is to simplify the construction and to provide a stacker which shall possess superior advantages with 15 respect to durability and efficiency.

With this object in view the invention consists of certain features of construction and combination of parts, which will be hereinafter fully described and claimed.

20 In the accompanying drawings, Figure 1 is a longitudinal sectional view of the rear portion of a thrashing-machine embodying my invention. Fig. 2 is a cross-section of the discharge-pipe on line $x x$ of Fig. 1. Fig. 3 is a 25 perspective view of my improved stacker. Fig. 4 is a longitudinal sectional view taken through the automatic shifting mechanism. Fig. 5 is a plan view of the same. Fig. 6 is a side elevation of the rear portion of the 30 thrasher-frame, and Fig. 7 is a sectional view on line $y y$ of Fig. 5.

In the drawings, A denotes a rear end portion of the thrasher-frame, to the lower portion of which is mounted the fan-casing B, 35 which is arranged obliquely to the length of the thrashing-machine. The top of the casing is formed with an opening through which the straw to be stacked is fed. The casing has secured to its bottom a journal-box f , 40 which projects upward into the casing and is in the form of a hollow truncated cone. A fan-shaft g is journaled in box f and has a central bore h intersected near its lower end by transverse openings. Near the upper end 45 of the shaft and secured thereto is a hub or spider i , to which the blades j of the fan C are attached. To the extreme upper end of the shaft is secured a grease-cup l , over which is placed a conical cap m , by which the grease- 50 cup is protected from violence and the straw deflected from the center to the blades of the fan. In this connection it will be noticed that

the conical box f directs the dust and chaff from the center of the fan-box toward the ends thereof, where they will be more exposed 55 to the action of the fan and be blown through the discharge-pipe. The fan is rotated by the power-shaft b , which is provided with a gear c in mesh with a gear j , secured to the lower end of the shaft g .

D denotes a platform which is secured to the rear end of the thrasher-frame at a point above the fan-casing. A metal plate E is supported on said platform and is provided with a central aperture surrounded by an annular 65 groove or seat n , in which are placed anti-friction-balls o . On the balls o is placed a turn-table F, having in its upper and lower faces about a center aperture grooves p and q , and about its periphery a series of cogs or teeth 70 r . The turn-table is provided with a downwardly-projecting short sleeve s , which projects into the central aperture in the plate E and also with an upwardly-projecting short sleeve t . Antifriction-balls u are placed in 75 the groove q , and placed over them is a binding-plate K, supported on sleeves or spools v , through which bolts w are passed into the plate E to hold the plate K in position.

To the sleeve t is secured an elbow-section 80 a' of the discharge-pipe L. Another section, b' , has its lower end connected with the fan-box, while its upper end projects upward through the openings in the platform and plate E, and almost contacts with the lower 85 end of the section a' . The adjacent ends of these two sections of the discharge-pipe are surrounded by the sleeve s of the turn-table, which tightly engages the ends and forms an air-tight joint.

M denotes a band or ring which is bolted to the upper end of the sleeve t , and from which project rearward arms c' . A pipe-section e' has an elbow f' , which passes down over the elbow-section a' , and is connected to 95 the arms c' by arms d' , so as to have a swinging movement therewith. The arms d' may be connected to the section e' in any suitable manner—as, for instance, by a ring or band N, as shown, which is cast integral with the 100 arms.

Supporting-standards O are secured to the ring M, one on each side of the discharge-pipe, the upper ends of said standards being

secured together by a pin g^2 , on which is journaled a sheave-wheel h' . A brace-rod i is attached to the pin g^2 with its upper end, and its lower end is secured to lugs j' projecting from the ring M . To the lugs j' are secured vertical bars k' , supported by a brace l' . A worm O' is journaled at the upper end of the bars k' and engages a worm-wheel m' , secured to the end of the winding-drum n^2 , journaled between said bars k' . This worm is provided with a hand-wheel p' . A cord q' connects a clamping-ring x' , secured to the outer end of pipe-section e' , to the winding-drum n^2 . By turning the hand-wheel p' to wind up the cord q' the outer end of the discharge-pipe may be raised. A reverse movement of the crank to unwind the cord will lower the discharge-pipe. To lengthen or to shorten the discharge-pipe I have provided novel means whereby section r' thereof may be drawn telescopically on and over section e' . To this end chain-wheels s' , supported on lugs projected from rings $N N'$, secured to the section e' , are provided with an endless chain t' . A rod u' has one end secured to the lower run of the chain by a bolt v' , while its other end is secured to the forward end of the section r' . By drawing the upper run of the chain forward the rod u' will be moved back, and thereby carrying out section r' , thus lengthening the discharge-pipe. A reverse movement will draw the rod u' and section r' forward, thus shortening the pipe.

To rotate the table I have provided a shaft H , which is journaled in boxes a^2 on the platform D . On one end of said shaft is fixed a worm G that engages the worm-teeth r on the periphery of the turn-table F , and on the other end of the shaft is mounted a crank-wheel P , by turning which the table F , with the upper sections a' , e' , and r' of the discharge-pipe, will be rotated to oscillate or swing the discharge-pipe over the straw-stack or to turn it forward and over the machine for transportation.

To automatically oscillate the outer or rear end of the discharge-pipe or stacker, I have secured to shaft H gear-wheels $Q Q'$, and on driving-shaft R , which is journaled in boxes a^3 , are loosely mounted gear-wheels $S S'$, one of which, S' , engages wheel Q' on shaft H , the other engaging an intermediate wheel T , journaled on a stud-shaft a^4 , said wheel T engaging wheel Q . On shaft R between the wheels $S S'$ is a clutch U , secured to said shaft in a sliding relation by a spline or other device, and on the inner faces of the wheels $S S'$ are provided corresponding clutches a^5 . Adjacent to the clutch is pivotally secured an operating-lever W having right-angle prongs a^6 that embrace the body of the clutch U between the clutch-heads a^7 . The lever W extends under the segmental rim X , on which are provided downwardly-projecting pins a^8 that engage the end portion of the lever W . On the under side of the lever W is pivoted a coil-spring a^9 , one end of which is secured to

the lever, the other end to the plate a^{10} . On the outer end of the shaft R is mounted a pulley Z . In operation the pulley Z , having a belt engagement with a similar pulley on the thrashing-machine, will continuously rotate the shaft in one direction. The clutch having engagement with one of the wheels $S S'$ will rotate the shaft H in one direction. The worm G , rotating the table F , will carry one of the pins a^8 against the side of the end portion of the lever W . The pin a^8 will move the lever over to one side until the pin a^8 passes the end of the lever, which will then be drawn back by the spring a^9 and will throw one of the clutches U in engagement with one of the wheels $S S'$, thereby reversing the movement of the shaft H , turn-table and discharge-pipe. This movement will continue until the other pin a^8 engages the opposite side of the lever W and reverses the movement of the parts. In operation the straw and the chaff will fall naturally on the "discharger" or "blower," (as the fan and its box may be properly termed,) placed, as it is, obliquely to the body of the thrasher. The straw then will be discharged through the discharge-pipe to the place of stacking.

For convenience in packing for transportation section e' may be detached from its support, section b' detached from the chamber B , and the support D removed from the thrasher-frame, thereby decreasing the length of the machine.

Having thus described my invention, what I claim is—

1. In a pneumatic straw-stacker, the combination of the centrally-apertured supporting-plate, having a circular groove or seat, a revoluble table provided with a coincident aperture, and with upwardly and downwardly projecting sleeves, said table having annular grooves or seats on its upper and lower faces, balls placed in the groove of the plate, balls placed in the upper groove of the turn-table, a binder-plate for securing the latter balls in position, a pneumatic discharge-pipe having the adjacent ends of two of its sections terminating within one of the sleeves of the turn-table whereby an air-tight joint is formed, substantially as set forth.

2. In a pneumatic straw-stacker, the combination of the supporting-plate, E , turn-table, F , having peripheral teeth, and oppositely-projecting sleeves, a binder-plate, balls located between the binder-plate and the turn-table and between the turn-table and the plate, E , a pneumatic discharge-tube having the adjacent ends of two of its sections terminating within one of the sleeves and snugly fitting the same to form an air-tight joint, and a worm, G , for engaging the teeth of and rotating the turn-table, substantially as set forth.

3. In a pneumatic straw-stacker, the combination of the discharge-pipe having a telescoping section, rings, N and N' , secured to one of said pipes and provided with upwardly-projecting lugs between which are supported

chain-wheels, s' , s' , a chain, t' , a rod, u' , one end of which is secured to the telescoping section of the discharge-pipe and the other to the chain, substantially as set forth.

5 4. In a pneumatic straw-stacker, a dis-
charger comprising a hub, h , blades, i , ar-
ranged at right angles to the hub, an aper-
tured shaft, k , journal-box, f , a grease-cup at
the upper end of the shaft, a conical cap, m ,
10 covering the grease-cup, means to rotate the
discharger, and a fan box or casing in which
the discharger is located, substantially as set
forth.

5. In combination, in a pneumatic stacker,
15 a circular receiving-chamber disposed ob-
liquely to the thrasher, and provided at its
bottom with an upwardly-projecting journal-
box which extends within the chamber at the
center thereof and deflects the straw and chaff
20 to the sides and ends of said chamber, a revo-
luble discharger comprising a shaft disposed
at right angles to the bottom of the receiving-
chamber, a hub mounted on one end of said
shaft, discharge-blades secured thereto, the
25 other end of said shaft being journaled in said
box, a conical cap secured to said hub which,
in conjunction with the upwardly-projecting
journal-box, deflects the straw and chaff to
the sides and ends of the chamber within the
30 path of movement of the blades, substantially
as set forth.

6. In a pneumatic straw-stacker, the combi-

nation with a revoluble support, a discharge-
tube having a telescoping section, chain-
wheels journaled to said discharge-pipe, a 35
chain engaged with said wheels, and a rod one
end of which is attached to the chain and the
other to the telescoping section, substantially
as set forth.

7. The combination with a horizontal sup-
porting-frame of a thrashing mechanism and
separator, a stationary circular receiving-
chamber, obliquely disposed to said frame,
provided at its bottom with an upwardly-
projected journal-box extending within said 45
chamber, a shaft journaled in said box, dis-
charge-blades secured to said shaft, a conical
cap secured above said journal-box, and in
conjunction with the said box, serving to de-
flect the straw and chaff to the sides and ends 50
of the chamber, within the path of movement
of the blades, a stationary tube centrally to
the side of said chamber extending upwardly
and rearwardly to a horizontally-disposed rev-
oluble support, and a discharge-pipe adapted 55
to oscillate about said support or turn for-
wardly over the machine, substantially as set
forth.

In testimony whereof I have hereunto set
my hand this 25th day of May, A. D. 1895.

ALLEN A. RUSSELL.
